ALLOVER BED CANOPY TO ADMINISTER OXYGEN

Thaddeus A. Taylor, Lufkin, Tex.

Application July 13, 1951, Serial No. 236,506

10 Claims. (Cl. 128—191)

1

The present invention relates to improvements in bed canopies, oxygen tents and the like and more particularly to all-over-bed canopies or tents to administer oxygen to a sick patient, and particularly adapted for use with refrigeration and oxygen supply means of standard makes.

Usually heretofore oxygen tents, canopies and the like have not been sufficiently sealed because there is provision only to tuck the bottom edge under the mattress and there is a great loss of oxygen through the mattress and around the edge of the canopy. Also when the tent or canopy is removed from under the mattress for nursing care there is still further loss in oxygen concentration in the tent.

The present invention greatly reduces oxygen loss by providing in combination with the upper part of the tent a sealed base section of gas-tight material for either enclosing the entire mattress or for resting on top of the mattress, whereby all mattress undertucking is eliminated and all nursing care and treatment of the patient in the interior of the upper part of the tent may be performed through slide fastener sealed openings at the head, foot and sides of the tent without material loss of oxygen concentration.

Accordingly an object of the invention is to provide a gas-tight canopy or the like, which may be mounted to completely cover the top of the mattress as a unit or which may be arranged to completely enclose the mattress, whereby any passage of oxygen and air through the mattress material fails to reduce oxygen concentration and only a small liter of flow is needed.

Another object is to provide a novel bed canopy for administering oxygen, which is formed of two separable upper and lower sections, the lower section or bottom section being of generally durable permanent non-transparent material and formed to enclose the bottom and sides of a mattress, the upper or top section being of transparent material detachable from the relatively more permanent non-transparent bottom section without disturbing the mattress or a patient reclining thereon, whereby new top sections can be replaced when torn or worn out and whereby the bottom section which is less likely to be damaged may continue to be used with each new top section.

A further object is to provide slide fasteners completely around the head and foot of the upper edge and lower edge of the respective bottom and top sections of the canopy, whereby the sections may be separated and connected at the head or foot of the canopy with a minimum of time and

effect to facilitate nursing care and various forms of treatment.

Still a further object is to provide slide fastener sealed openings in the upper section of the canopy at the side, foot and end of the bed for nursing care and treatment of the patient during the process of administering the oxygen without much loss in concentration of oxygen in the tent.

- 10 Yet another object is to provide slide-fastener means in the wall of the upper section for a sealing connection around the intake and outlet conduits of an ice cooling unit or a refrigeration unit for use with or without the oxygen supply.
- 15 Still another object is to provide as an article of manufacture a separable two part oxygen tent of simple, durable and inexpensive gas-tight material, wherein either part of the tent may be sold separately for replacement purposes if desired.

20 With these and other objects in view which will become apparent as the invention is fully understood, the same resides in the novelty of construction, combination and arrangement of elements hereinafter described in detail and distinctly claimed in the appended claims.

The description should be read in conjunction with the accompanying drawings wherein:

25 Figure 1 is a general perspective view of a bed showing the mattress enclosed and completely housed inside the tent and showing an air conditioning unit and oxygen tank with inlet and outlet pipes thereof sealed in the side of the tent by double slide fasteners.

30 Figure 2 is a partial cross-section view taken along the line 2—2 of Figure 1 at the head of the canopy.

35 Figure 3 is a partial cross-section view taken along the line 3—3 at the foot of the canopy.

40 Figure 4 is a partial perspective view showing an arrangement for oxygen supply with a safety valve, and refrigerated air inlet and outlet conduits enclosed by double slide fasteners.

45 Figure 5 is a horizontal cross-section view taken around the canopy on the line 5—5 of Figure 1.

50 Figure 6 is a partial vertical cross-section view taken on a line transverse a snap fastener closure formed of overlapping plies of material.

55 Figure 7 is a side elevational view of the closure in Figure 6 closed and sealed, and

Figure 8 is a side elevational view of the closure in Figure 6 open for nursing care or special treatment of a patient in the tent or canopy.

Referring in detail to the drawings and first with particular reference to Figures 1 and 2, there is shown a bed A, a mattress B, a canopy supporting stand C at the head of the bed and a canopy support D at the foot of the bed. As illustrated the canopy 10 is completely enclosing the mattress B and comprises a bottom non-transparent section 11, which covers the bottom and most of the sides of the mattress. The upper rim of the section 11 is edged with spaced apart lower sections 12 and 13 respectively of slide fasteners 14 and 15, which cooperate with similarly spaced sections 16 and 17 fastened to the lower edge of the upper canopy section 18 of said respective slide fasteners 14 and 15. Thus slide fastener section 12 of the canopy bottom section and slide fastener section 16 of the upper canopy section when joined together encompass or encircle the mattress at the head of the bed from each side, while the fastener lower section 13 and the upper fastener section 17 encircle the mattress at the foot of the bed from each side to the respective fastener anchors or terminal lugs 19-19 and 20-20 on the opposite side. The terminal lugs of each slide fastener are positioned in aligned spaced apart relation on each end of a multi-ply snap fastener closure for an opening 21 as shown in Figure 8.

This multi-ply closure is gas-tight and comprises a looped over strip with the overlapping outer flap 23 secured to the upper section 18 of the tent by stitches 24, in Figure 6. The outer flap carries the female parts of two or more snap fasteners 25 and 26, while the inner leg or flap of the loop 22 carries a plurality of male parts 27, 28, 29, 30, 31 and 32, which snaps connect with the cooperating female parts 27', 28', 29', 30', 31' and 32' of a doubled over flap 33 stitched to the lower tent section 11. As shown in Figures 6 and 8 the flap 33 fits between flaps 22 and 23 so that male snap fastener elements 27 through 32 on flap 22 snap fit with the female fastener elements on flap 33. After these are snapped together then the outer flap 23 folds over and female snap elements 25 and 26 engage with male elements 25' and 26' on the exterior side of flap 33. Disconnection of these snap fasteners make the opening 21 available for uses, such as stomach drainage, chest abscess drainage and the like.

Most all patients taking oxygen need blood transfusions or glucose and it is important to provide closure means for this purpose in the walls of the canopy so there will be very little loss of oxygen concentration. As illustrated in Figure 1 there are numerous sealed slide fastener openings for these and similar purposes. For example, at the foot of the canopy 10 is a slide fastener 34 adapted to provide access to the feet of the patient when the tent is set up. The foot of the tent or canopy 10 is held above the feet of the patient by elongated straps 35 and 36, respectively, spaced apart on each side of the slide fastener 34. These straps are stitched to the exterior of the canopy 10 and include a snap fastener element on each of their respective ends so that when the straps are looped around an upstanding U-shaped support 37 having right angled feet 38 and 39, which fit under the mattress B, the foot of the canopy is held elevated above the mattress B to enhance the patient's comfort.

The head of the canopy is held in elevated operating position by means of tabs 41 having one end secured to the exterior of the dome 40 of the canopy, said tabs each having their respective free ends formed with an opening for the

hooked ends of support arms 42. When thus held elevated the sides of the canopy flare downwardly and outwardly over the mattress B. On the side opposite to the snap fastener elements 12 and 13 encircling the head of the canopy is a slide fastener closure 43, see Figures 1 and 2. This closure 43 when opened is used for giving treatment to the patient and the slide fastener may be closed around the arm of the doctor or nurse giving the treatment or around the arm of the patient for transfusions and the like, thereby avoiding any appreciable loss of oxygen during the treatment. In addition to closure 43 and substantially perpendicular to the same are slide fastener closures 44 and 45 for giving medication, water and nourishment. These closures like 43 may be closed around the arm of the nurse or person giving the treatment or the like.

Similar slide fastener openings may be on the opposite side, if desired, and just below the dome 40 on this side are two spaced apart multiple zipper closures 46 each for connection with an ice-cooled unit or with an air conditioning unit 48 by encircling the inlet and outlet pipes 49 and 49a, respectively, see Figures 1 and 4. An oxygen tank 50 with a supply line 51 may also lend into the canopy at this connection.

The base section 11 of the canopy 10 may be mounted on top of the mattress if desired by using the anchoring tabs 52 secured in each corner and on each side to the exterior of the base section material by stitches 53. The free end of each tab hangs down over the sides of the mattress B and pin fasteners 54 or the like secure the tabs to the mattress material.

Operation and use

The operation and use of the present invention is believed to be apparent from the foregoing detailed description. For example, to completely enclose the mattress B, the base section 11 is applied to the bottom of the mattress and sides with the upper canopy section 18 detached, next the dome 40 of the canopy and its tabs 41 are attached to the hooks on the support arms 42 and the main slide fastener anchors of the respective top and bottom canopy sections are locked together as well known in the slide fastener art. The slide elements 14 and 15 are adjacent their respective pairs of anchor elements on their side of the canopy and may now be slid at will around their respective paths of travel to enclose the head of the mattress and the foot of the mattress. Prior to closing the main slide fasteners 14 and 15, the canopy foot support 37 is put in position at the foot of the mattress and straps 35 and 36 are looped over the top bar of the support and snapped into holding position.

This now causes the canopy to be held to proper shape and the patient may be placed on the mattress before the main slide fasteners are closed on one side of the mattress.

The same general operation takes place when using the base section 11 on top of the mattress B and the same is secured to the mattress by tabs 52 and pin fasteners 54.

It often is desirable to fold back the upper section 18 of the canopy and open the main slide fasteners around the head and foot of the canopy permitting the rear side to stay fastened. To facilitate folding back of the upper section 18, there are provided handle loops 60 adapted to be gripped by the nurse to raise and fold over the side of the canopy 10.

The air conditioner unit and oxygen supply are

readily attached by inserting the connecting pipes 49 within the double slide fastener openings as shown in Figure 4 on the side of the dome portion 40 and it is of course understood that such connections may be provided at the rear of the dome portion instead of the side, if desired. A safety valve 61 is shown in Figures 1 and 4, and another valve, not shown, if desired may be mounted in the wall of the upper section 18. Also to provide a safety vent for excess pressures 10 in the tent, the slide fasteners 14 and 15 may be left slightly open at the side, thereby permitting escape of excessive air and oxygen and also CO₂ which is exhaled by the patient. A graduated air meter may be connected to the oxygen gauge so that a certain amount of air may be given with the oxygen.

Thus there is provided an all-over-bed oxygen canopy that can be operated on top of the mattress or with the mattress completely housed inside the same. Also there is provided a canopy with a top completely removable from the base section of the canopy by separating head and foot slide fasteners, one around the head and one around the foot of the canopy, said top section having further slide fastener openings for nursing care and treatment of the patient without much loss of oxygen in the canopy, and double slide fastener openings for air tight connection with conduit connections from an air conditioning unit and/or an oxygen supply tube.

While the foregoing specification describes and the drawings illustrate the specific details of this invention, it is to be understood that the same is not limited by these details and is therefore 35 susceptible to changes and modifications within the scope of the appended claims without a departure from the spirit of the invention.

I claim:

1. A canopy for administering oxygen, having an oxygen supply opening therein, comprising a sealed base section for covering a mattress, a sealed upper section adapted to be suspended above said base section, and slide fastener means for detachably connecting said upper section to the said base section.

2. A canopy of flexible foldable material for administering oxygen, having an oxygen supply opening therein, comprising a sealed base section for completely enclosing the bottom and sides of a mattress, a sealed upper section adapted to be suspended above the top of the mattress, and separable fastener means for detachably connecting said upper section with said base section, thereby forming a substantially gas-tight enclosure completely around and over the mattress.

3. A canopy for administering oxygen, having an oxygen supply opening therein, comprising a sealed base section enclosing the bottom and sides of a mattress, a sealed upper section adapted to be suspended above the top of the mattress, and a pair of slide fasteners detachably connecting said upper section with said base section, one of said fasteners extending around the head of the canopy and the other of said fasteners extending around the foot of the canopy, whereby either the head or the foot of the canopy may be opened for access to the interior of the canopy.

4. A canopy for administering oxygen, having an oxygen supply opening therein, comprising a sealed base section for covering a mattress, a sealed upper section adapted to be suspended above said base section, fastener means for detachably connecting said upper section to the

5 base section, and tabs with pin fasteners secured to the exterior corners and sides of said sealed base section, said tabs hanging adjacent the sides of a mattress on which said base section is resting, whereby said pin fasteners may be secured to the sides of the mattress.

5. An oxygen tent for maintaining a high concentration of oxygen per low liter of flow comprising a non-transparent base section open at the top, said top rim having the lower elements of a pair of slide fasteners secured around its peripheral edge, a transparent upper section open at the bottom, said bottom rim having the upper elements of said pair of slide fasteners around its peripheral edge, and a pair of slide fasteners one for each of said adjacent lower and upper elements, one of said slide fasteners being slidable around the head of the tent to join the said sections together and the other of said slide fasteners being slidable around the foot of the tent to join said sections together.

6. An oxygen tent for maintaining a high concentration of oxygen per low liter of flow comprising a non-transparent base section open at the 25 top, said top rim having the lower elements of a pair of slide fasteners secured around its peripheral edge, a transparent upper section open at the bottom, said bottom rim having the upper elements of said pair of slide fasteners around its peripheral edge, a pair of slide fasteners one for each of said adjacent lower and upper elements, one of said slide fasteners being slidable around the head of the tent to join the said sections together and the other of said slide fasteners being slidable around the foot of the tent to join said sections together, additional slide fastener closed openings in the walls of the upper transparent section at the foot and side portions thereof, and conduit connecting openings formed 30 in a side wall of said upper section for connection with an air conditioner and/or an oxygen supply pipe.

7. An oxygen tent comprising a closed bottom section and a detachable closed top section, slide 45 fasteners for connecting said sections together, said bottom section being shaped to contain a mattress and said top section having a dome portion and downwardly flaring side and front portions extending to said bottom section, supporting tabs secured to the exterior of said dome portion for connection with supporting means, straps secured to the exterior of the top section near the foot of said front portion, and support means for holding the foot of said front portion elevated 50 when the straps are fastened around said support, whereby said top section is supported in operative position over a mattress contained within said closed bottom section.

8. A canopy for administering oxygen, having 60 an oxygen supply opening therein, comprising a sealed base section for enclosing the bottom and sides of a mattress, a sealed upper section adapted to be suspended above the top of the mattress, and a multi-ply snap fastener closure for an elongated horizontal opening in said upper section, said closure having a foldable loop of material with snap fastener elements on the legs of the loop and an intermediate flap insertable between the legs of the loop including snap fastener elements engageable with said fastener elements on the legs of the loop when folded together.

9. The oxygen tent described in claim 6, wherein 65 said conduit connecting openings are each closable around the inlet and outlet conduits of

said air conditioner or the like by means of double slide fasteners.

10. An oxygen tent for use with standard oxygen supply and refrigerator units comprising a detachable closed lower section and a top closure section securable to said lower section having a dome portion and a foot portion, said dome portion including a pair of spaced apart openings each closed by a multiple slide fastener, said respective openings each being adapted to receive the free ends of a respective inlet and outlet conduit from a refrigeration unit.
